TYPEWRITING MACHINE

Lewis C. Myers, Freeport, and George F. Handley, Glendale, N. Y., assignors to Royal Typewriter Company, Inc., New York, N. Y., a corporation of New York

Original application December 17, 1931, Serial No. 581,702. Divided and this application filed September 26, 1932. Serial No. 634,968

27 Claims. (Cl. 197—178)

This invention relates to new and useful improvements in typewriting machines generally, although more particularly to a column stop mechanism therefor, and constitutes a division of our 5 co-pending application Serial No. 581,702, filed Dec. 17, 1931.

Among the several objects of our invention are to provide a typewriting machine with a series of column stops which are arranged at the rear of 10 the machine; to mount said column stops on a supporting frame for swinging movements in a direction fore and aft of the machine; and to automatically and frictionally retain each column stop in either its active or inactive position.

15 In the drawings:—

Figure 1 is a partial rear elevation of a typewriting machine embodying the column stops of my invention.

Figure 2 is a vertical sectional view showing 20 the release of the carriage escapement mechanism and also showing one of the denomination stoplevers in engagement with one of the column stops.

Figure 3 is an enlarged top plan view showing a 25 plurality of the column stops mounted on the rack bars.

Figure 4 is an enlarged vertical sectional view showing the column stop in its normal or inactive position, the actuating finger for moving 30 the column stop to its active or operating position, and the stop restoring means in operative position.

Figure 5 is a view similar to Figure 4 but showing 35 the stop operating finger in position after it has moved the stop to its active position, the stop restoring device being shown in section.

Figure 6 is a perspective view showing the application of the tie plate to the upper and lower 40 rack bars which support the column stops.

Figure 7 is a perspective view showing portions 45 of the upper and lower rack bars which are respectively provided with transverse grooves for receiving the tie plate.

Figure 8 is an enlarged vertical sectional view 50 showing one of the column stops in its active or operating position, and the stop restoring means in its normal or inactive position.

Figure 9 is a partial top plan view of one end 55 of the upper and lower rack bar assembly of the stop frame, and

Figure 10 is a perspective view showing the adjustable connection at one end between the stop frame and the end plate of the carriage, the parts being shown in separated relation.

The invention is illustrated as applied to the 55 well known Royal machine but many of the features thereof are applicable to other typewriters.

The machine includes the usual main frame 1 which supports the usual track upon which runs a carriage 3 having end plates 4—4 which support 60 a platen 5. An escapement rack bar 6 is pivotally supported on the carriage and is normally drawn by a spring 7 into engagement with a pinion 8 mounted on the usual shaft. An escapement wheel 9 is mounted to rotate with the pinion 8 65 and cooperates with the usual escapement dog not shown.

Supported by the end plates 4, 4 of the carriage and disposed in rear of the platen 5 is a column stop frame A which includes upper and lower 70 rack bars 10 and 11 respectively. These bars are held in parallel spaced relation through the medium of end plates 12, 12. Each plate is provided with upper and lower angular recesses 75 13 and 14 to receive correspondingly shaped extensions on the ends of the rack bars and thereby prevent turning of the bars relative to each other and relative to the plates. Upper and lower clamping screws 15, 16 serve to clamp each plate 12 against the upper and lower bars. Rigidly 80 connected with each end plate 12 is an outwardly projecting threaded stud 17 having a flat upper surface 17^a which fits into a correspondingly shaped opening 17^b in the adjacent end plate 4 of the carriage. Clamping nuts 18, 18 are 85 mounted on the threaded 17 and are clamped against the opposite faces of the end wall 4 of the carriage. The upper and lower stop bars 10 and 11 are rectangular in cross section. The lower face of the upper bar 10 is formed with a series of transversely extending grooves 19 and the upper face of the lower bar 11 is formed with a series of transversely disposed grooves 20, the 90 grooves 19, 20 being arranged in pairs and spaced apart at distances corresponding to letter space 95 intervals. Supported on the stop frame A is a series of column stops B, there being one of these stops for each pair of upper and lower grooves 19 and 20. In other words, these stops B are 100 mounted on the stop frame A at letter space

intervals. Each stop is of H-shaped construction and includes upwardly converging front and rear arms 21 and 22 and downwardly diverging front and rear legs 23 and 24, and a cross bar or connecting portion 25. Each stop B is positioned on the frame A so that the arms 21, 22 are disposed on opposite sides of the upper rack bar 10 and the legs 23, 24 are disposed on opposite sides of the lower rack bar 11, the cross bar or bridge 25 extending between the bars 10 and 11 and into the upper and lower transverse grooves 19 and 20. The upper ends of the arms 21, 22 are rounded and the distance between these ends is substantially equal to the width of the rack bar 10 so as to permit the stop to swing from an inactive forward position to an active rearward position or vice versa, the rounded ends of the arms constituting pivots or fulcra for the stop. The lower ends of the legs 23, 24 are spaced apart a distance considerably greater than the width of the lower rack bar 11 so as to permit the stop being swung from one extreme position to the other, the legs cooperating with the lower rack bar 11 to limit the swinging movement of the stop. The height of the cross bar or bridge 25 of the stop is less than the distance between the top wall of the groove 19 and the bottom wall of the groove 20. The lower edge of the bridge portion 25 adjacent the rear leg 24 is provided with a flat 26 which rests on the bottom wall of the groove 20 when the stop B is in its inactive or inoperative position, as shown in Figure 4. The lower edge of the bridge portion 25 between the forward leg 23 and the flat 26 is formed with a recess 27 to form a clearance and thereby permit the free rearward swinging of the stop B to the position shown in Figure 8. It is desirable to frictionally retain each stop B in each of its extreme positions. To this end, each stop B is provided with a spring 28 which is in the form of a spring wire bent between its ends to form upper and lower spring arms 29 and 30 respectively, the bend of the spring engaging a headed stud 31 which is attached to the stop. The arms 29, 30 extend forwardly between the upper and lower rack bars 10 and 11, and the free end of the lower arm 30 is provided with an offset 32 which is located in a seat 33 formed in the front edge of the stop. The free end of the upper arm 29 is curved upwardly and downwardly to form a cam which has sliding engagement with the lower face of the rack bar 10 when the stop B is in its active position as shown in Figure 8 and with the lower front corner of the upper rack bar 10 when the stop B is in its inactive position as shown in Figure 4. Thus when the stop B is in its active position as shown in Figure 8, the lower angled edge of the bridge 25 between the front leg 23 and the flat 26 is seated against the rear upper corner of the wall of the transverse groove 20 and is frictionally held thereagainst by the tension of the spring 28 due to the arm 29 thereof bearing against the under face of the upper rack bar 10. When the stop B is moved to its inactive position, as shown in Figure 4, the free end of the upper arm 29 of the spring 28 will snap over the lower front corner of the upper rack bar 10 and the flat 26 will be yieldably retained in contact with the lower wall of the groove 20. It will, therefore, be seen that the stop B is capable of being rocked rearwardly to an active position or forwardly to an inactive position and that yieldable means are employed for automatically and frictionally retaining the stop in either of its extreme positions.

In order to retain the center portions of the upper and lower rack bars 10 and 11 against relative movement, we have provided a tie plate 34 which is formed with upper and lower angular openings 35 and 36 respectively for receiving the upper and lower rack bars 10 and 11, as shown in Figures 6 and 7. The upper faces of the upper and lower rack bars 10 and 11 are respectively formed with transverse recesses 37, 38 for respectively receiving the upper walls of the openings 35 and 36. The lower end of the plate 34 extends downwardly below the opening 36 and terminates in an arm 39 which underlies the lower rack bar 11. A filler block 40 is disposed between the arm 39 and the lower face of the rack bar 11 and a clamping screw 41 passes through the arm 39 and the block 40 and is threadedly engaged in the lower rack bar 11, thereby securely retaining the rack bars 10, 11 and the tie plate 34 against relative movement.

A plurality of key-selected denominational stop levers E are pivotally mounted on the rear of the machine frame for cooperation with the column stops B in the usual manner. A key-operated setting finger 59 is located in front of the column stops B and when the finger is moved rearwardly it will engage and swing the registering column stop B to its active or operating position.

Our invention also includes a stop restoring device G which is manually movable for cooperation with the tabular stops B for returning the latter to their normal or inactive positions upon movement of the carriage in either direction. This stop restoring device G is mounted on the main frame 1 of the machine at a point in rear of the stops B. This device includes a U-shaped frame 122 including a top 123 having depending legs 124, 125 which are pivoted by a stud 126 and a pivot screw 127 to forwardly extending arms 128, 128 of a bracket 129 which is secured to the supporting bracket 61 by screws 130, as shown particularly in Figures 1 and 3. The axes of the pivots 126, 127 are in alignment and in a plane extending parallel with the rack bars 10 and 11 so as to permit the restoring device G to be swung toward and away from the column stops B. The top 123 projects forwardly beyond the supporting legs and the forward edge of said top is formed into a camming surface having a high point 131 located centrally between the attaching legs 124, 125. Two rollers 132, 133 are journaled on vertical axes 134, 135 carried by the top 123. These rollers are disposed on opposite sides of the high point 131 of the camming edge of said top, the camming edge projecting forwardly beyond said roller as clearly shown in Figure 3. In other words, the high point 131 of the camming edge is intermediate the rollers 132, 133, and said rollers project forwardly beyond the camming edge at opposite ends thereof. The rollers 132, 133 function to move easily the column stops B in their first or initial movement over the high point X of the cam surfaces on the cross bars 25 of said stops. The leg 124 projects downwardly below the pivot stud 126 to form a stop arm 136 which is adapted to engage a fixed stop 137 fixed to the arm 128 of the attaching bracket 129 to limit the rearward swinging movement of the device as shown particularly in Figure 8. A coil spring 138 has its upper end engaged with an ear 139 attached to the frame 122 and its other end engaged in an ear 140 secured to the attaching bracket 129. This spring 138 functions to normally retain the restoring de-

vice G in its inoperative position with the arm 136 bearing against the stop 137 as shown in Figure 8. The arm 125 of the frame 122 extends below the pivot screws 127 and terminates in a stop arm 141 which is adapted, when the restoring device G is swung forwardly to operative position, to engage the bracket 129 and thereby limit the forward movement of the device. In order to assist in moving the device to its operative position, we have provided an upwardly extending fingerpiece 142 which is attached to the top 123 of the pivot frame 122. Thus when it is desired to restore the column stops B to their normal or inactive positions, the operator engages the fingerpiece 142 and swings the restoring device G forwardly so as to cause the stops B to first engage one or the other of the rollers 132, 133, depending on the direction of movement of the carriage, and then to engage the high point 131 of the cam edge of the top 123, the parts being so arranged that the high point 131 of the cam will completely restore the column stops B to their normal positions.

From the foregoing, it will be observed that we have provided a typewriting machine with a series of column stops which are arranged at the rear of the machine; that said column stops are mounted on a supporting frame for swinging movements in a direction fore and aft of the machine; that each column stop is automatically and frictionally retained in either its active or inactive position; and that a normally inoperative stop restoring device is adapted to be manually moved forwardly into position to be engaged by the column stops during movement of the carriage in either direction to thereby restore all of the column stops to their normal or inactive positions.

We claim:—

40 1. In a tabulating mechanism for typewriting machines, a stop frame comprising upper and lower rack bars respectively provided on their lower and upper faces with transverse grooves spaced apart at letter space intervals, and a plurality of column stops respectively mounted in each pair of upper and lower grooves and swingable from an inactive to an active position and vice versa.

50 2. In a tabulating mechanism for typewriting machines, a stop frame comprising upper and lower rack bars respectively provided on their lower and upper faces with transverse grooves spaced apart at letter space intervals, a plurality of column stops respectively mounted in each pair of upper and lower grooves and swingable from an inactive to an active position and vice versa, and a spring connected to each column stop and cooperating with the frame to frictionally retain the stop in either of its extreme positions of movement.

60 3. In a tabulating mechanism for typewriting machines, a stop frame comprising upper and lower rack bars respectively provided on their lower and upper faces with transverse grooves spaced apart at letter space intervals, and a plurality of column stops respectively mounted in each pair of upper and lower grooves and swingable from an inactive to an active position and vice versa, each stop comprising spaced arms embracing the upper rack bar, spaced legs embracing the lower rack bar, and a bridge connecting the arms and legs and disposed between the bars and slidably engaging in the associated upper and lower grooves of the bars.

70 4. In a tabulating mechanism for typewriting

machines, a stop frame comprising upper and lower rack bars respectively provided on their lower and upper faces with transverse grooves spaced apart at letter space intervals, and a plurality of column stops respectively mounted in each pair of upper and lower grooves and swingable from an inactive to an active position and vice versa, each stop comprising spaced arms embracing the upper rack bar, spaced legs embracing the lower rack bar, and a bridge connecting the arms and legs and disposed between the bars and slidably engaging in the associated upper and lower grooves of the bars, the arms converging and having pivotal engagements with the outer faces of the upper bar, and the legs diverging and being spaced apart a distance greater than the width of the lower bar and respectively engageable with the outer faces thereof to limit the movements of the stop.

5. In a tabulating mechanism for typewriting machines, a stop frame comprising upper and lower rack bars respectively provided on their lower and upper faces with transverse grooves spaced apart at letter space intervals, and a plurality of column stops respectively mounted in each pair of upper and lower grooves and swingable from an inactive to an active position and vice versa, each stop comprising spaced arms embracing the upper rack bar, spaced legs embracing the lower rack bar, and a bridge connecting the arms and legs and disposed between the bars and slidably engaging in the associated upper and lower grooves of the bars, the arms converging and having pivotal engagements with the outer faces of the upper bar, and the legs diverging and being spaced apart a distance greater than the width of the lower bar and respectively engageable with the outer faces thereof to limit the movements of the stop, the height of the bridge being less than the distance between the upper and lower walls of the associated grooves, and a spring mounted on each stop for cooperation with the upper bar to frictionally retain the stop in either extreme position of movement.

6. In a tabulating mechanism for typewriting machines, a stop frame comprising upper and lower rack bars respectively provided on their lower and upper faces with transverse grooves spaced apart at letter space intervals, and a plurality of column stops respectively mounted in each pair of upper and lower grooves and swingable from an inactive to an active position and vice versa, each stop comprising spaced arms embracing the upper rack bar, spaced legs embracing the lower rack bar, and a bridge connecting the arms and legs and disposed between the bars and slidably engaging in the associated upper and lower grooves of the bars, the arms converging and having pivotal engagements with the outer faces of the upper bar, and the legs diverging and being spaced apart a distance greater than the width of the lower bar and respectively engageable with the outer faces thereof to limit the movements of the stop, the height of the bridge being less than the distance between the upper and lower walls of the associated grooves, the lower edge of the bridge adjacent one leg being formed with a flat and the edge between the flat and the other leg being formed with a clearance recess, and a 2-armed spring mounted on each stop, one arm bearing against the upper wall of the groove of the upper bar and the other arm being anchored to the stop.

7. In a tabulating mechanism for typewriting machines, a stop frame comprising upper and lower rack bars respectively provided on their lower and upper faces with transverse grooves spaced apart at letter space intervals, a plurality of column stops respectively mounted in each pair of upper and lower grooves and swingable from an inactive to an active position and vice versa, and a tie plate connecting the rack bars centrally between the ends thereof. 10
8. In a tabulating mechanism for typewriting machines, a stop frame comprising upper and lower rack bars respectively provided on their lower and upper faces with transverse grooves spaced apart at letter space intervals, a plurality of column stops respectively mounted in each pair of upper and lower grooves and swingable from an inactive to an active position and vice versa, the upper surface of the upper bar and the upper surface of the lower bar being each provided with a transverse groove, a tie plate having upper and lower openings for receiving the rails, the upper walls of the openings fitting into the transverse upper grooves of the bars, the plate extending laterally below the lower bar, a filler block disposed below the lower bar and the laterally extending end portion of the tie plate, and a screw connecting the end portion of the tie plate, the filler block and the lower bar. 20
9. In a tabulating mechanism for typewriting machines, the combination with a stop frame including spaced upper and lower bars, of a column stop disposed therebetween and mounted therebetween on a floating pivot to swing transversely of said bars, the stop including a depending stop leg adapted to engage the lower bar to limit the swinging movement of the stop in one direction and also including a recess-forming seat engageable with the lower bar when the stop leg engages said bar, and a spring for exerting downward pressure on the stop to retain the same in its extreme position of movement with the stop leg engaging the lower bar and with the seat in engagement with the lower bar. 30
10. In a tabulating mechanism for typewriting machines, the combination with a stop frame including spaced upper and lower bars, of a column stop disposed therebetween and mounted therebetween on a floating pivot to swing transversely of said bars, the stop including a depending stop leg adapted to engage the lower bar to limit the swinging movement of the stop in one direction and also including a flat lower edge engageable with the lower bar when the stop leg engages said bar, and a spring for exerting downward pressure on the stop to retain the same in its extreme position of movement with the stop leg engaging the lower bar and with the flat lower edge in engagement with the lower bar, said spring being rebent to form upper and lower arms, the lower arm engaging the column stop and the upper arm engaging the upper bar. 40
11. In a tabulating mechanism for typewriting machines, the combination with a stop frame including spaced upper and lower bars, of a column stop disposed therebetween and mounted therebetween on a floating pivot to swing transversely of said bars, the stop including a depending stop leg adapted to engage the lower bar to limit the swinging movement of the stop in one direction and also including a flat lower edge engageable with the lower bar when the stop leg engages said bar, and a spring for exerting downward pressure on the stop to retain the same in its extreme position of movement with the stop leg engaging the lower bar and with the flat lower edge in engagement with the lower bar, said spring being rebent to form upper and lower arms, the lower arm engaging the column stop and the upper arm terminating in a cam end for engaging the side of the upper bar opposite the stop leg when the column stop is positioned with the flat lower edge thereof in engagement with the lower bar. 50
12. In a tabulating mechanism for typewriting machines, the combination of a stop frame including spaced upper and lower bars, the upper bar having flat sides, and a column stop disposed between the bars and including two upwardly extending arms having free pivotal connections with the flat sides of the upper bar whereby the stop may be swung transversely of the bar from one side thereof to the other. 60
13. In a tabulating mechanism for typewriting machines, the combination of a stop frame including spaced upper and lower bars, the upper bar having flat sides, and a column stop disposed between the bars and including two upwardly extending arms having free pivotal connections with the flat sides of the upper bar whereby the stop may be swung transversely of the bar from one side thereof to the other, the stop being provided with depending legs for alternately engaging the lower bar to limit the extreme swinging movements of the stop. 70
14. In a tabulating mechanism for typewriting machines, the combination of a stop frame including spaced upper and lower bars, the upper bar having flat sides, a column stop disposed between the bars and including two upwardly extending arms having free pivotal connections with the flat sides of the upper bar whereby the stop may be swung transversely of the bar from one side thereof to the other, the stop being provided with depending legs for alternately engaging the lower bar to limit the extreme swinging movements of the stop, and cooperating means between the column stop and the bars for retaining the stop in either extreme position thereof. 80
15. In a tabulating mechanism for typewriting machines, the combination of a stop frame including a bar having the lower face thereof provided with a transverse groove, and a column stop pivoted to the bar to swing transversely thereof and guided by the walls of said groove, the stop being free from contact with the top of said groove. 90
16. In a tabulating mechanism for typewriting machines, the combination of a stop frame comprising upper and lower bars, the lower face of the upper bar being provided with a transverse groove, and a column stop disposed between the bars and pivoted to the upper bar to swing transversely thereof and guided by the walls of said groove, the stop being free from contact with the top of said groove and provided with depending stop legs engageable with opposite sides of the lower bar to limit the swinging movements of said stop. 100
17. In a tabulating mechanism for typewriting machines, the combination of a stop frame comprising upper and lower bars, the lower face of the upper bar being provided with a transverse groove, and a column stop disposed between the bars and provided with upwardly extending arms having free pivotal connections with the side 110

- faces of the upper bar whereby the stop may be swung transversely of the upper bar and guided by the walls of said groove, the stop being free from contact with the top of said groove and provided with depending stop legs engageable with opposite sides of the lower bar to limit the swinging movements of said stop. 80
18. In a tabulating mechanism for typewriting machines, the combination of a stop frame comprising upper and lower bars, the lower face of the upper bar being provided with a transverse groove, and a column stop disposed between the bars and provided with upwardly extending arms having free pivotal connections with the side faces of the upper bar whereby the stop may be swung transversely of the upper bar and guided by the walls of said groove, the stop being free from contact with the top of said groove and provided with depending stop legs engageable with opposite sides of the lower bar to limit the swinging movements of said stop, and a spring mounted on the stop and having sliding contact with the upper bar to yieldably retain the stop in engagement with the lower bar. 85
19. In a tabulating mechanism for typewriting machines, the combination of a stop frame comprising upper and lower bars, the lower face of the upper bar being provided with a transverse groove, a column stop disposed between the bars and provided with upwardly extending arms having free pivotal connections with the side faces of the upper bar whereby the stop may be swung transversely of the upper bar and guided by the walls of said groove, the stop being free from contact with the top of said groove and provided with depending stop legs engageable with opposite sides of the lower bar to limit the swinging movements of said stop, the height of the stop being less than the distance between the top and bottom walls of the grooves, the lower edge of the stop adjacent one leg being provided with a flat for engaging the adjacent end of the bottom wall of the lower groove when the stop is in one extreme position, and with a recess-forming seat between the flat and the other leg for engaging the opposite end of the bottom wall of the lower groove when the stop is in its other extreme position, and a spring mounted on the stop and having sliding contact with the upper bar to yieldably retain the stop in engagement with the lower bar. 90
20. In a tabulating mechanism for typewriting machines, a main frame element, a carriage element, a stop frame mounted on one of said elements, a plurality of column stops supported on the stop frame for independent movements from an inactive position to an active position, or vice versa, and a manually operable stop restoring device pivotally mounted on the main frame in rear of the column stops and movable forwardly from a normally inoperative position to an operative position for successively engaging the active column stops and returning them to inactive positions during movement of the carriage. 100
21. In a tabulating mechanism for typewriting machines, a main frame element, a carriage element, a stop frame mounted on one of said elements, a plurality of column stops supported on the stop frame for independent movements from an inactive position to an active position, or vice versa, and manually operable means mounted on the other of said elements for successively restoring the actively positioned column stops to inactive positions upon movement of the carriage, said device including a U-shaped frame pivoted to swing about a horizontal axis, the top of the U-shaped frame having a front cam edge adapted to be engaged by the column stops when the frame is in operative position, and a spring for normally retaining the device in its inoperative position. 105
22. In a tabulating mechanism for typewriting machines, a main frame element, a carriage element, a stop frame mounted on one of said elements, a plurality of column stops supported on the stop frame for independent movements from an inactive position to an active position, or vice versa, and manually operable means mounted on the other of said elements for restoring the actively positioned column stops to inactive positions upon movement of the carriage including a movable frame containing a roller and a camming edge engageable in sequence by the stops. 110
23. In a tabulating mechanism for typewriting machines, a stop frame, a plurality of column stops supported on the frame for independent movements from an inactive position to an active position, or vice versa, and manually operable means for restoring the actively positioned column stops to inactive positions upon movement of the carriage in either direction including a movable frame containing spaced rollers and an intermediate camming edge, one of the rollers and the camming edge being engageable in sequence by the stops. 115
24. In a tabulating mechanism for typewriting machines, the combination with a stop frame including spaced bars, of a column stop disposed therebetween and mounted therebetween on a floating pivot to swing transversely of said bars, the stop including a stop leg adapted to engage one bar to limit the swinging movement of the stop in one direction and also including a flat lower edge engageable with the said bar when the stop leg engages said bar, and a spring for exerting pressure on the stop to retain the same in its extreme position of movement with the stop leg engaging the bar and with the flat lower edge in engagement with the bar, said spring being rebent to form arms, one arm engaging the column stop and the other arm engaging the other bar. 120
25. In a tabulating mechanism for typewriting machines, the combination with a carriage including end plates, of a stop frame including spaced parallel rack bars disposed between the end plates, a plurality of column stops mounted on said bars for transverse movements relative thereto, and separate means connecting and supporting said frame on the end plates for adjustments therebetween longitudinally of the rack bars. 125
26. In a tabulating mechanism for typewriting machines, the combination with a carriage including end plates, of a stop frame including spaced parallel rack bars disposed between the end plates and rigidly connected at their ends by tie-plates, a plurality of column stops mounted on said bars for transverse movements relative thereto, and separate means connecting and supporting said frame on the end plates for adjustments therebetween longitudinally of the rack bars, said adjusting means each comprising a threaded stud fixedly secured to each tie-plate and extending longitudinally through an opening in the adjacent end plate, and adjustable clamping means mounted on the threaded stud for engagement with the opposite faces of the end plate. 130
27. In a tabulating mechanism for typewriting machines, the combination with a carriage including end plates, of a stop frame including spaced parallel rack bars disposed between the end plates and rigidly connected at their ends by tie-plates, a plurality of column stops mounted on said bars for transverse movements relative thereto, and separate means connecting and supporting said frame on the end plates for adjustments therebetween longitudinally of the rack bars, said adjusting means each comprising a threaded stud fixedly secured to each tie-plate and extending longitudinally through an opening in the adjacent end plate, and adjustable clamping means mounted on the threaded stud for engagement with the opposite faces of the end plate. 135
28. In a tabulating mechanism for typewriting machines, the combination with a carriage including end plates, of a stop frame including spaced parallel rack bars disposed between the end plates and rigidly connected at their ends by tie-plates, a plurality of column stops mounted on said bars for transverse movements relative thereto, and separate means connecting and supporting said frame on the end plates for adjustments therebetween longitudinally of the rack bars, said adjusting means each comprising a threaded stud fixedly secured to each tie-plate and extending longitudinally through an opening in the adjacent end plate, and adjustable clamping means mounted on the threaded stud for engagement with the opposite faces of the end plate. 140
29. In a tabulating mechanism for typewriting machines, the combination with a carriage including end plates, of a stop frame including spaced parallel rack bars disposed between the end plates and rigidly connected at their ends by tie-plates, a plurality of column stops mounted on said bars for transverse movements relative thereto, and separate means connecting and supporting said frame on the end plates for adjustments therebetween longitudinally of the rack bars, said adjusting means each comprising a threaded stud fixedly secured to each tie-plate and extending longitudinally through an opening in the adjacent end plate, and adjustable clamping means mounted on the threaded stud for engagement with the opposite faces of the end plate. 145
30. In a tabulating mechanism for typewriting machines, the combination with a carriage including end plates, of a stop frame including spaced parallel rack bars disposed between the end plates and rigidly connected at their ends by tie-plates, a plurality of column stops mounted on said bars for transverse movements relative thereto, and separate means connecting and supporting said frame on the end plates for adjustments therebetween longitudinally of the rack bars, said adjusting means each comprising a threaded stud fixedly secured to each tie-plate and extending longitudinally through an opening in the adjacent end plate, and adjustable clamping means mounted on the threaded stud for engagement with the opposite faces of the end plate. 150

ing machines, the combination with a carriage including end plates, of a stop frame including spaced parallel rack bars disposed between the end plates and rigidly connected at their ends 5 by tie-plates, a plurality of column stops mounted on said bars for transverse movements relative thereto, and separate means connecting and supporting said frame on the end plates for adjustments therebetween longitudinally of the rack 10 bars, said adjusting means each comprising a

threaded stud fixedly secured to each tie-plate and extending longitudinally through an opening in the adjacent end plate, said stud having a flat face and the receiving opening being of a shape corresponding to the cross sectional shape of the stud, and adjustable clamping means mounted on the threaded stud for engagement with the opposite faces of the end plate.
